UNITED STATES PATENT OFFICE

CHESTER L. DAVIS, OF WASHINGTON, DISTRICT OF COLUMBIA, ASSIGNOR TO WIRED RADIO, INC., OF NEW YORK, N. Y., A CORPORATION OF DELAWARE

SIGNALING SYSTEM

Application filed August 21, 1928. Serial No. 300,979.

My invention relates to signaling systems in general and more specifically to systems for the transmission and reception of pictures by space radio or wired radio systems.

5 An object of my invention is to provide an improved system for the transmission of pictures.

Another object of my invention is to provide an improved system for the reception 10 of pictures.

Still another object of my invention is to provide a system for the reception of pictures, views and the like without the necessity of the usual methods of synchronizing 15 the receiver with the transmitter.

A further object of my invention is to provide a system for the transmission of pictures, views and the like whereby a receiving system, employing a glow-discharge device 20 similar to that described in my co-pending application Serial No. 299,501, filed Aug. 14, 1928, entitled Glow discharge device, may receive the transmitted pictures without distortion of the reproduction and without 25 troublesome synchronization as usually required.

A better understanding of the signaling system of my invention can be had by referring to the specification following and to 30 the accompanying drawings, wherein, Figs. 1 and 2 are illustrations showing the transmitting part of the signaling system of my invention; Figs. 3 and 4 are illustrations showing the receiving part of the signaling 35 system of my invention; Fig. 5 is a graph showing the operation of the transmitting part of the signaling system of my invention; Figs. 6 and 7 are schematic circuit arrangements employed in the receiving 40 system and Fig. 8 is a graphical representation showing the operation of the signaling system of my invention.

In systems heretofore employed in the transmission and reception of pictures, views 45 and moving pictures, an elaborate method of synchronization has been employed to synchronize the receiver with the transmitter. This has heretofore been necessary due to the mechanical system of scanning disks employed at both the transmitter and receiver.

A scanning disk has heretofore been employed at both receiver and transmitter. The purpose of the scanning disk is to interrupt the beam of light or luminous radiation at frequent intervals and direct a small 55 beam to the desired area. To receive a transmitted picture without distortion it is necessary to have the scanning system at the receiver in perfect synchronism with the scanning system employed at the transmitter. 60 The disadvantages of such a system are well known to those skilled in the art. In the signaling system of my invention, such synchronization is eliminated and the simplicity of operating procedure is greatly reduced 65 thereby. A better understanding can be had by referring to the accompanying drawings.

Fig. 1 shows the transmitter employed in the signaling system of my invention. The object represented at H is illuminated by 70 suitable means 30 and rays of light from the object H enter the lens 6 which are interrupted by scanning disk 7. Scanning disk 7 may be of any suitable construction or may be a shutter or perforated band. A common 75 method of scanning employs a disk having a plurality of perforations around the periphery thereof, each perforation being located at different distances from the center of the disk. A photoelectric device 5 receives the rays of light broken up and of varying intensity. Variations in the intensity depend upon the relative light and dark areas of the picture or scene to be transmitted. Scanning member 7 is rotated by 80 motor 8 or any other suitable rotary device. In systems heretofore employed, the variations of the electrical energy caused by the variations in the resistance of photo-electric device 5 and indirectly from variations in 85 the intensity of the light rays, are caused to modulate the transmitter and the signal thus transmitted at a frequency corresponding to the frequency characteristics of the oscillatory circuit thereof. In the signaling system of my invention, the frequency of the transmitted energy is varied corresponding 90 to the position of the scanning member 7. A continuously variable frequency controlling member, herein represented as capacity 9, is 95 100

associated with the scanning member 7 whereby variations in the frequency are caused at each rotation of the scanning member 7. Thus variations of frequency are transmitted, each frequency having a value of current corresponding to the resistance of photo-electric device 5 at each instant. Capacity 9 is herein illustrated connected in series with photo-electric device and the input of transmitter 1. Capacity 9 may be shunted by an impedance unit. Input terminals 3 may connect to the modulation circuit of a transmission system. Connected to the control electrode and cathode electrode of a thermionic tube, the amplified energy in the anode circuit would have a frequency value depending upon the value of the exciting frequency from capacity 9 and any value of impedance employed therewith. The transmitted signaling energy will be modulated at a continuously variable audio frequency. The current or percentage modulation depends upon the resistance of photo-electric device 5. It is obvious that an impedance may be caused to vary with the rotation of the scanning member accomplishing a similar periodically varying audio frequency modulation. The high frequency signaling energy may be associated with a load circuit 2.

Fig. 2 shows another form of the signaling system of my invention wherein the reference characters correspond to those of Fig. 1. Photo-electric device 5 is associated with the input terminals 3 of an amplifier-modulator unit 10. Amplifier-modulator unit 10 may comprise thermionic tubes, the terminals 3 connecting to the control electrode and cathode electrode of a thermionic tube amplifier. Variations in the intensity of light entering lens 6 and caused to be incident upon light-sensitive or photo-electric device 5 produce variations of current which are amplified and caused to modulate the generated energy of oscillator 11. The output of oscillator 11 may be associated with any suitable load circuit 2^a, 2^b. The high frequency circuit of oscillator 11 or load circuit 2^a, 2^b may be controlled by periodically changing frequency unit 9, herein represented as a capacity unit connected in series with the ground circuit 2^a. It is possible that the energy in the load circuit may be of great value. In such a case the periodically changing frequency unit 9 may be associated with the master oscillator unit, if such is employed, or the input circuit of the oscillator. In this arrangement the high frequency signaling energy is not of a constant frequency value but covers a band of different frequencies in repeating successions. Any variable frequency unit may be associated with scanning member 7 for causing a variation in the frequency of the transmitted signaling energy.

Figs. 3 and 4 are illustrations showing the

receiving unit of the signaling system of my invention. Collecting system 2^a—2^b receives a signal as transmitted from a transmitter similar to that shown in Fig. 1. In Fig. 3 the high frequency signaling energy is amplified, rectified and the audio frequency signal is amplified by unit 14. Unit 14 may comprise a thermionic tube circuit arrangement. The output terminals 15 of the audio frequency amplifier may be associated with glow-discharge device 12—13. Glow-discharge device 12—13 may be of the design as described in my co-pending application Serial No. 299,501 filed Aug. 14, 1928. Standing waves are set up in winding 13. Winding 13 is enclosed by an evacuated envelope 12 containing an inert gas such as neon, krypton or any gas which will give a luminous radiation. Potential nodes and anti-nodes are set up in winding 13, the position along winding 13 depending on the frequency of the modulated energy. The potential loops or where the potential is maximum is where the luminous radiation will take place. This position shifts with the frequency. The extent of luminous radiation or intensity of light at such position corresponds to the light and dark portions of the transmitted picture or scene.

Fig. 4 shows another modification of the receiving unit employed in the signaling system of my invention. This unit is designed to operate and reproduce pictures and views similar to the unit shown in Fig. 3, however it is adapted to receive a periodically varying frequency and modulated signal as transmitted by a transmitter designed similar to that shown in Fig. 2. The high frequency signaling energy is received by collector system 2^a—2^b. Collector system 2^a—2^b may have aperiodic frequency characteristics. The high frequency signaling energy may be amplified by amplifier 16. Amplifier 16 may have sufficient aperiodic frequency characteristics whereby the band of frequencies transmitted may be amplified. A glow-discharge device 12—13 is connected to any suitable output circuit of amplifier 16 where standing waves are set up. The luminous radiation and shifting of the illuminated area is similar to the operation of glow-discharge device 12—13 of Fig. 3.

Fig. 5 is a graphical representation of the relation between the rotation of the scanning disk at the transmitter and the frequency of the transmitter circuit. In the arrangement shown in Fig. 1 the frequency variation is in the band of audio frequencies. The graphical representation would therefore show the relation between the audio frequency band of modulation or particular frequency of modulation, represented by the character F in the graph, and the position of the scanning disk represented in degrees of rotation.

Fig. 6 is a schematic illustration showing the immediate connections to the glow-discharge device 13. Circuits 18^a and 18^b, having inherent frequency characteristics may be associated with the source of signaling energy by switch members 18 and 19 respectively. Circuits 18^a and 18^b may be common to the winding 13 of the glow-discharge device. Terminals A and B may be connected to the source of signaling energy. Standing waves are set up in the winding 13. By adjusting the frequency characteristics of circuits 18^a and 18^b the potential loops may be adjusted along the conductor. Thus the potential distribution in winding 13 may be controlled. Without this adjustment the receiver would operate on only the frequency band corresponding to the frequency characteristics of the respective winding 13.

Fig. 7 is a schematic diagram showing the adjusting circuit 18-18^a for shifting the potential loop along the length of winding 13 in the glow-discharge device. A metal plate 20 may be placed adjacent to winding 13. Winding 13 may have one end open, the other end and metal plate 20 connected to the source of signaling energy A-B. The arrangement of metal plate 20, constituting one electrode of the glow-discharge device is described in my co-pending application, Serial No. 299,501 filed Aug. 14, 1928.

Fig. 8 is a graphical representation showing one relation between the wave length characteristics of the glow-discharge device and the wave length of the received signaling energy. The wave length of the signaling energy is represented by the vertical line λ . The wave length characteristics of the glow-discharge device may be represented by the horizontal line λ' . The ratio of the wave length of the signaling energy λ to the wave length characteristics of the glow-discharge device λ' may be approximately, two to one. The graph may also be taken to represent the response area as shown by the line "response".

At the transmitting station the scanning member selects different areas of the picture to be transmitted. Simultaneously and interdependent with such selection of the different areas, a frequency variation of the transmitted energy is effected. Different frequencies are transmitted for different areas of the picture. Such frequencies may be audio frequency modulations of the carrier frequency or may be variations of the carrier frequency itself. The scanning device may be any suitable arrangement such as the spiral disk commonly employed where the lines are drawn across the horizontal length of the picture or where they are drawn across the vertical length of the picture. Other scanning means such as vibrating tuning forks moving in different planes may be employed. Such scanning means are well known to those skilled in the art. The scan-

ning may be in diagonal order if so desired, however the design of the glow discharge device at the receiver will have to be governed accordingly or the frequency variation modified to agree with the method of scanning and the design of the glow discharge device at the receiver. The design of the glow discharge device at the receiver must be modified in accordance with the type of scanning employed and of course with the proper frequency characteristics to respond to the variable frequency energy. The position of the nodes or of the antinodes of energy in the glow discharge device may be employed to reproduce either a positive or negative of the original picture. Suppose as an example of design we choose to make the inductance of each length of wire in the horizontal plane of the value n and that 41 of such lengths are employed giving us a total inductance of approximately $41n$. The total frequency variation at the transmitter which corresponds to the different areas of the picture will be such as to shift the potential distribution in the glow discharge device the full length of the complete inductance $14n$. It follows that as each of the apertures in the scanning disk scan one line horizontally across the picture, the frequency of the transmitted energy is varied sufficiently to cause a change in the distribution in the glow discharge device at the receiver over one length of wire in the horizontal plane. The succeeding aperture may not scan the next line of the picture at the transmitter but scan the third line. The usual frequency variation during the interval between the scanning by the two apertures may be effected. The next exposure at the receiver will be the third horizontal line because of the frequency shift at the transmitter. At the bottom of the picture the scanning may now continue from the bottom to the top interleaving with the lines previously drawn across the picture in the horizontal plane or may continue from the second horizontal line from the top, followed by the even numbered lines. The frequency varying device may be caused to respond through a second cycle where the first frequency transmitted would be such as to cause a change in the potential distribution along the second horizontal line where the inductance thus far would be of the order of $2n$. Many different arrangements may be employed all with equally satisfactory results, some arrangements provide greater persistency of vision than do others and are less costly to manufacture, however, accuracy in the initial selection of the glow discharge device is the main requisite to satisfactory results.

In Figs. 5 and 8 the numerical values shown are arbitrary and it is not intended to restrict the embodiments of my invention

thereby. In Figs. 1 to 4 inclusive, the periodically varying frequency unit and the glow-discharge device may be employed in many different circuit arrangements. The periodically varying frequency unit may include 5 a variable capacity as shown, a variable impedance, a variable inductance or a combination of the above.

A brief summary of the operation of my 10 invention is as follows: At the transmitter the rays of luminous energy corresponding to different portions of the picture are obtained by means of the scanning member. Different frequencies of the transmitted energy correspond to different portions of the 15 picture. At the receiver the incoming energy is distributed along a conductor which distribution changes with the frequency of the incoming energy and occupies positions along the conductor corresponding to the respective portions of the picture transmitted.

The advantages of the signaling system of my invention are many. Among them, the following are most obvious:

- 25 1. Transmission and reception of moving or stationary scenes or pictures without distortion.
2. Simplicity of operation at both the transmitting and receiving ends.
- 30 3. Synchronizing dispensed with at the receiving end.

I realize that many modifications of the signaling system of my invention are possible without departing from the spirit of my invention and it is to be understood that my 35 invention shall not be restricted by the foregoing specification or by the accompanying drawings but only as defined in the scope of the appended claims.

40 What I claim as new and desire to secure by Letters Patent of the United States is as follows:

- 45 1. A television receiver comprising in combination means for receiving variable frequency energy, variable intensity apparatus comprising a coil having its inductance distributed in a plurality of sections disposed in horizontal planes parallel to each other and a glow discharge tube enveloping the different sections of said inductance.
- 50 2. In a television receiving system the combination of a luminously responsive device comprising an inductance coil having its inductance distributed along a plurality of parallel sections in different horizontal planes and a luminously responsive gas envelope surrounding said inductance coil for indicating the potential distribution along said coil.
- 55 3. In a television receiving system the combination of a circuit for receiving signaling energy of variable frequency corresponding to different shaded areas of a transmitted picture, an inductance comprising a plurality of parallel longitudinally extending sections

connected in series with said circuit and luminous gas means enveloping said sections for indicating the potential distribution therein.

4. In a television receiving system a signal 70 receiving circuit, a luminously responsive reproducing screen comprising in combination a plurality of parallel longitudinally extending inductance sections connected with said circuit, a gaseous glow discharge tube 75 positioned adjacent said sections whereby different portions of said tube luminously indicate the relative potential distributed along the respective inductance sections.

5. In a television receiving systems, a signal 80 receiving circuit, a receiving screen comprising a multiplicity of inductance members connected with said circuit and extending in a plurality of parallel planes, said members being associated with a body of luminously responsive gas whereby changing potential distribution in said inductance members causes changes in luminosity from different areas of said body of gas.

6. A method of indicating positions by 90 variable frequency energy which consists in establishing potential nodes along different sections of luminously responsive inductance units arranged in parallel paths.

7. An apparatus of the class described comprising a wave receiving inductance element divided into a plurality of parallel longitudinally extending sections and means for automatically and luminously indicating changes in position of a potential node established along said element.

8. The method of indicating positions which consists in changing the location of potential nodes in accordance with a variable signal and causing said changing of nodes to be luminously visible along a plurality of parallel sections of inductance extending in a longitudinal plane.

9. In the art of transmitting vision, a receiving apparatus for waves of varying 110 lengths comprising a luminously responsive inductance divided into a plurality of parallel and longitudinally extending sections.

10. In the art of transmitting vision, a receiving apparatus for waves of varying 115 lengths comprising a luminously responsive inductance divided into a plurality of parallel and longitudinally extending sections, said sections varying in luminosity in accordance with the different areas of a transmitted picture.

11. In the art of transmitting vision, receiving apparatus for waves of varying 125 lengths comprising means for setting up standing waves in a luminously responsive inductance, said inductance comprising a plurality of parallel arranged conductors connected in series and glow discharge apparatus adjacent said conductors for indicating the potential distribution therein.

12. In a television system, a conductor bent upon itself in a plurality of parallel paths and means for causing a luminous spot to move along said conductor according to the potential distribution therein in said plurality of parallel paths. 70
13. In the art of transmitting vision, means for receiving waves of varying lengths, causing a crest of said waves to be luminously visible and causing the movement of said crest along a plurality of inductance sections in parallel relation. 75
14. In the art of transmitting vision employing a line scanning system for picture transmission, a luminously responsive receiving screen comprising a plurality of conductors electrically connected in series and positioned in parallel planes of a number and in the manner substantially the same as the lines drawn across the transmitted picture. 80
15. In the art of transmitting vision, a luminously responsive screen comprising a plurality of electrical conductors arranged in a plurality of substantially parallel planes corresponding to the transmitted lines of a picture. 85
16. In the art of transmitting vision employing a line scanning system for picture transmission, a luminously responsive receiving screen comprising a plurality of electrical conductors associated with a body of inert gas, said conductors being arranged in a plurality of parallel planes corresponding in number and arrangement to the different lines described across the transmitted picture. 90
17. A television system comprising means for transmitting variable frequency signals, means for receiving variable frequency signals, and a screen for visually reproducing the variable frequency signals comprising a multiplicity of parallel extending luminous portions electrically connected to each other and with said receiving means. 95
18. A television system comprising means for transmitting variable frequency signals, means for receiving variable frequency signals, a screen for visually reproducing the variable frequency signals comprising a multiplicity of parallel extending luminous portions electrically connected to each other and with said receiving means, and means connected with said screen for shifting the position of potential nodes therein to predetermined positions along said parallel extending luminous portions. 100
19. In a television system, means for transmitting signaling energy over a variable range of frequencies, means for receiving the transmitted energy, a screen comprising a plurality of parallel extending portions connected with said receiving means and a tuning element connected to said parallel extending portions for predetermining the position of potential nodes along said parallel extending portions. 105
20. In a television system, means for transmitting variable signaling energy, means for receiving the transmitted energy and a screen comprising a plurality of parallel extending portions connected in series, and a variable inductance connected between said parallel extending portions and said receiving means for predetermining the position of potential nodes along said parallel extending portions. 110
